CENTRIFUGAL SWITCH

Ernst Walter Rickmeyer, Berkeley, Ill., assignor
to Jefferson Electric Company, Bellwood, Ill.,
a corporation of Illinois

Application November 16, 1945, Serial No. 629,957

13 Claims. (Cl. 200—80)

1

The present invention relates to mercury switches of the centrifugal type. More particularly, it is concerned with the time delay element for a mercury switch of this type.

A mercury switch that embodies the present invention comprises a switch envelope or shell that is divided into two chambers by a partition, through which partition the mercury is adapted to pass under certain conditions and at a predetermined rate of flow. In one chamber are disposed a pair of spaced electrical contacts that are normally insulated from each other. The gap between the contacts is bridged by a body of mercury that is disposed in this first chamber, and when this gap is thus bridged the electrical circuit through the switch is completed. When the mercury is caused to pass through the partition into the second chamber so as to lower the level of the mercury in the first chamber, the bridge between the spaced contacts is broken, thereby breaking the electrical circuit through the switch.

This dividing partition is adapted to support the mercury in the first chamber and allows the mercury to pass into the second chamber only when sufficient pressure is applied by the mercury against the partition to force the mercury to flow through restricted openings in the dividing partition. This force is created by spinning the switch shell about an axis that will throw the mercury against the dividing partition or by accelerating the shell in a direction that will accomplish the same result.

The present invention contemplates the use of a partition that comprises sintered particles of metal, such as steel or nickel, that are spaced apart to provide a multitude of voids therebetween. These voids serve as the restricted passages through which the mercury may flow. By varying the particle sizes and the pressure used when sintering these particles together, it is possible to vary the degree of restriction in these passages, and hence to produce time delay elements having a wide range of different time delay characteristics. It is also possible to produce these different characteristics by varying the length of the restricted passages.

It is therefore an object of the present invention to provide time delay elements for a mercury switch of this type that have predetermined time delay characteristics.

It is also an object of the invention to produce a means and method for varying the time delay characteristics in accordance with specific requirements.

2

The foregoing constitute some of the principal objects and advantages of the present invention, others of which will be made apparent upon a reading of the following description and from the drawings, in which:

Fig. 1 is a plan view of a rotating or spinning device in which is mounted a circuit controlling switch embodying the present invention;

Fig. 2 is an enlarged vertical sectional view 10 through a mercury switch embodying one form of the present invention;

Fig. 3 is a top plan view of the switch shown in Fig. 2;

Fig. 4 is a transverse sectional view taken on 15 the line 4—4 of Fig. 2;

Fig. 5 is a fragmentary vertical sectional view corresponding to Fig. 2 but showing a different form of the invention;

Fig. 6 is a view corresponding to Fig. 5 but 20 showing still a different embodiment of the invention;

Fig. 7 is a view corresponding to Figs. 5 and 6 but showing another form of the present invention;

Fig. 8 is a transverse sectional view through a 25 mercury switch, the view being taken on the line 8—8 of Fig. 7;

Fig. 9 is a view corresponding to Fig. 7 but showing still another form of the invention; and

Fig. 10 is a transverse sectional view through a 30 mercury switch, the view being taken on the line 10—10 of Fig. 9.

For purposes of illustration, specific embodiments of the invention have been selected, but it 35 is recognized that modifications will occur to the man skilled in the art, and it is intended that the embodiments shown may be modified without departing from the intended scope of the invention.

Referring to the drawings and particularly to Fig. 2, the invention is shown as embodied in a 40 mercury switch comprising a switch envelope or shell 15 that contains therein a cup-like time delay element 16, which divides the shell 15 into two chambers indicated at 17 and 18. The shell 15 has an offset portion providing an annular shoulder 19 upon which the cup 16 is supported.

The cup 15 is open at its upper end, through 45 which opening projects a contact element generally indicated at 20. A copper flanged element 21 is adapted to rest on the upper end of cup 16, and the contact member 20 is provided with an annular projection or flange 22 that is supported on the flanged element 21 and the top of the cup 16. A sealing ring or washer 23 is in-

serted between the flanged member 21 and the contact member 20. A second sealing washer 24 is mounted on top of the projection 22, and the upper end of the shell 15 is crimped over, as at 25, against the washer 24. The contact member 20 is thus sealed in place in the upper end of the shell 15.

This contact member 20, as shown, comprises a body portion 26 of Bakelite, or like material, that is molded about a cup-like conducting member 27 that projects through the body portion 26 and provides an exposed surface at 28 at the lower end of the contact member 20. This cup-like member 27 may be made of copper or like electrical conducting material.

Mercury normally fills the chamber 17 of the cup 16, as shown at 29. This mercury serves as an electrical conductor between the exposed portion 28 of the conducting member 27 and the wall of the cup 16. This cup 16 likewise is made of an electrical conducting material, and engages the wall of the shell 15, which likewise is made of a good electrical conducting material. A copper ring 30 surrounds the shell 15 and makes good electrical contact therewith. Thus, the circuit through the mercury can be traced from the conducting member 27, which constitutes one lead terminal, through the mercury 28, cup 16, shell 15, and finally through the ring 30, which constitutes the other lead terminal to the mercury switch.

The cup 16 constitutes the time delay element through which the mercury 29 passes in flowing into chamber 18. This cup is made of sintered particles of metal, such as steel or nickel, between which particles are provided the voids that constitute restricted passages. As shown, the entire cup 16 is made of these sintered metal particles, though it is recognized, of course, that the lower portion, or bottom only, of the cup 40 may be so made.

As shown in Fig. 1, the mercury switch indicated at 14 may be mounted on a disk 31 that is adapted to rotate about a shaft 32. The mercury switch 14 is mounted so that the upper end of the shell 15, shown in Fig. 2, is disposed closest to the shaft or axis of rotation 32. Thus, as the disk 31 is rotated in the direction of the arrow, the centrifugal force causes the mercury 29 to be urged against the bottom of the time delay cup 16.

When the mercury switch is at rest and during normal conditions of handling, the bottom of the cup 16 is adapted to support the mercury in chamber 17 without their being any leakage of the mercury into chamber 18. It is only upon the reaching of a predetermined centrifugal force resulting from the rotation of the disk 31 that the mercury 29 is caused to apply sufficient pressure against the bottom wall of cup 16 that this mercury is forced through the passages or voids between the sintered metal particles into the chamber 18. Because of the nature of the restricted passages between the particles and further due to the fact that the mercury entering the second chamber must displace the air or gas that is initially disposed in this second chamber, a certain time is required for the mercury 29 to flow into the second chamber. As soon as the level of the mercury is disposed below or out of contact with the exposed portion 28 of the contact member 20, the circuit through the switch 14 is broken.

As shown, the centrifugal force required to cause the mercury to flow through the passages

in the time delay cup 16 is created by the rotation of the disk 31. It is recognized, of course, that sufficient force may be provided in other ways, such, for example, by accelerating the mercury switch in a direction and to a sufficient degree to effect this same result.

As previously mentioned, the time required for the mercury 29 to flow through the restricted passages or voids between the sintered metal particles in cup 16 is dependent upon the degree of restriction and the length of the path through which both the mercury and the displaced air from chamber 18 must flow. The displacement of this air or gas from chamber 18 is in a direction counter to the flow of the mercury since this gas must flow from chamber 18 into chamber 17. In Fig. 6, a cup 34 is provided with its bottom wall having throughout its width a uniform thickness, and hence sintered particles that have undergone uniform pressure during the sintering process. Thus, in this form of the invention, the flow of mercury and gas through the bottom wall of the cup is more or less uniform throughout the entire area of the bottom.

In Fig. 2, on the other hand, the bottom wall is provided with a projecting portion 33 disposed substantially in the center portion of the wall. In forming this cup, the particles of metal that are disposed in this bulging portion 33 have undergone much less pressure during the sintering process than those particles disposed in those portions of the bottom wall removed from this central portion. In other words, the voids between the particles are much larger in the central portion of the bottom of cup 16 than are the voids in the remainder of the bottom wall. Thus, the flow of mercury and gas through the bottom of cup 16 is much faster than in the case of the cup shown in Fig. 6.

Thus, there is illustrated in Figs. 2 and 6 time delay cups 16 and 34 having two different characteristics. In the case of the form shown in Fig. 2, the time delay is relatively short, so that this type of cup would be used in a so-called fast acting switch. In Fig. 6, on the other hand, the time delay is considerably longer because of the much higher pressure utilized during the sintering process over the entire area of the cup bottom, and therefore the type of cup shown in Fig. 6 would be utilized in a slower operating switch.

In Fig. 5, the inner wall of the cup element 35 is curved at the bottom thereof so as to provide a bottom wall portion having a uniform thickness where this portion is of considerably less diameter than that shown in Fig. 6. In this form of the invention, the air transfer between chambers 18 and 17 would be reduced over that shown in Fig. 6 because of the longer path that would be required through the bottom wall in the regions of greater thickness. Thus, Fig. 5 represents a mercury switch having longer time delay characteristics than that shown in Fig. 6.

Figs. 7 and 8 illustrate two time delay cups having still different characteristics. In Fig. 7, the inner wall of the cup 36 is substantially hemispherical, as shown at 37, so as to provide a bottom wall having a non-uniform thickness throughout its area. Thus, in this form of the invention, if the center portion only of the wall 70 is of a thickness corresponding to that of the bottom wall of cup 34 (Fig. 6) then it can be seen that the length of the paths through the remainder of the bottom wall of cup 36 is greater than in the case of cup 34, and hence on an average the restriction to the flow of gas through

time delay cup 36 is greater than in the case of cup 34. Thus, Fig. 7 illustrates a mercury switch having still a greater time delay in its operation than in the case of any of the previously illustrated embodiments of the invention.

Fig. 9 illustrates a cup 38 whose inner walls, at least in the lower region of the cup, slope inwardly substantially parabolically to provide still different time delay characteristics. In this form of the invention, there is provided a relatively small bottom wall that is effective in allowing gas to transfer from chamber 18 to chamber 17. This embodiment of the invention illustrates a very slow operating switch.

It is thus seen from the foregoing that many variations in time delay characteristics can be provided by changing the shape and form of the bottom walls of the time delay cups. There obviously are other shapes and combinations of shapes which can be used to effect still different time delay characteristics.

I claim:

1. A mercury switch comprising a shell, a cup in the shell with the cup bottom spaced from both ends of the shell to provide two chambers, the cup bottom comprising sintered metal particles providing voids therebetween forming continuous passages through the cup bottom, the length of the passages in certain portions of the cup bottom being on an average greater than those in other portions of the cup bottom, and a body of mercury in one chamber adapted to flow through the passages into the other chamber.

2. A mercury switch comprising a shell, a cup in the shell with the cup bottom spaced from both ends of the shell to provide two chambers, the cup bottom comprising sintered metal particles providing voids therebetween forming continuous passages through the cup bottom, and a body of mercury in one chamber adapted to flow through the passages into the other chamber, the relative sizes and lengths of the passages being such as to allow freer flow of mercury through the center portion of the cup bottom than through other portions.

3. A mercury switch comprising a shell, a cup in the shell with the cup bottom spaced from both ends of the shell to provide two chambers, the cup bottom comprising sintered metal particles providing voids therebetween forming continuous passages through the cup bottom, and a body of mercury in one chamber adapted to flow through the passages into the other chamber, the relative sizes and lengths of the passages being such as to allow freer flow of mercury through certain portions of the cup bottom than through other portions.

4. A mercury switch comprising a shell, a cup in the shell with the cup bottom spaced from both ends of the shell to provide two chambers, the cup bottom wall comprising sintered metal particles, the space between the particles in one region of the bottom being larger than in other regions of the cup bottom, and a quantity of mercury in the shell adapted to pass through the said wall.

5. A mercury switch comprising a shell, a cup in the shell with the cup bottom spaced from both ends of the shell to provide two chambers, the cup bottom wall comprising compressed sintered metal particles, the spaces between the par-

ticles in the central region of the cup bottom being larger than in other regions of the cup bottom, and a quantity of mercury in the shell adapted to pass through the said wall.

6. A mercury switch comprising a shell, a cup in the shell with the cup bottom spaced from both ends of the shell to provide two chambers, the cup bottom wall comprising sintered metal particles, the one face of the cup bottom being bulged in the center portion thereof, and a quantity of mercury in the shell adapted to pass through the said wall.

7. A mercury switch comprising a shell, a cup in the shell with the cup bottom spaced from both ends of the shell to provide two chambers, the cup bottom wall comprising sintered metal particles, the inner side faces of said cup merging toward each other at the bottom of the cup, the outside faces of the cup being substantially flush throughout the height of the cup, and a quantity of mercury in the shell adapted to pass through the said wall.

8. A mercury switch comprising a shell, a cup in the shell with the cup bottom spaced from both ends of the shell to provide two chambers, the cup bottom wall comprising sintered metal particles, the inner surface of the cup bottom being curved while the outside bottom surface is substantially planar, and a quantity of mercury in the shell adapted to pass through the said wall.

9. A mercury switch comprising a shell, a wall in the shell spaced from both ends of the shell to provide two chambers, said wall comprising sintered metal particles, the space between the particles in one region being larger than in other regions of the wall, and a quantity of mercury in the shell adapted to pass through the said wall.

10. A mercury switch comprising a shell, a wall in the shell spaced from both ends of the shell to provide two chambers, the wall being porous, the pores in one region of the wall being larger than in other regions of the wall, and a quantity of mercury in the shell adapted to pass through the said wall.

11. A mercury switch comprising a shell, a wall in the shell spaced from both ends of the shell to provide two chambers, the wall comprising sintered metal particles, the spaces between the particles in the central region of the wall being larger than in other regions of the wall, and a quantity of mercury in the shell adapted to pass through the said wall.

12. A mercury switch comprising a shell, a wall in the shell spaced from both ends of the shell to provide two chambers, said wall comprising sintered metal particles, one face of the wall being bulged in the center portion thereof, and a quantity of mercury in the shell adapted to pass through the said wall.

13. A mercury switch comprising a shell, a wall in the shell spaced from both ends of the shell to provide two chambers, the wall comprising sintered metal particles, one surface of the wall being curved while the other surface is substantially planar, and a quantity of mercury in the shell adapted to pass through the said wall.

ERNST WALTER RICKMEYER.
